UNITED STATES PATENT OFFICE.

FRED E. SCHWALB, OF CHICAGO, ILLINOIS.

CONVEYING APPARATUS.

Application filed September 18, 1919. Serial No. 324,573.

To all whom it may concern:

Be it known that I, FRED E. SCHWALB, a resident of Chicago, Illinois, have invented a certain new and useful Improvement in 5 Conveying Apparatus, of which the following is a specification.

This invention relates to conveyors in general, but more particularly to those employed in handling coal, and especially to 10 the apparatus employed for transferring the coal from cars to places of storage, or to wagons or other means of transportation.

Generally stated, the object of the invention is to provide an improved portable conveyor which can be moved into position to receive the materials thereon, and which can be shifted out of the way when it is desired to move the cars or other portable receptacles from which the coal or other materials 20 are discharged onto the conveyor, so that the latter can be used for successively unloading the materials from a series of cars standing on a track.

It is also an object to provide certain details and features of construction and combinations tending to increase the general efficiency and the desirability of a conveyor of this particular character.

To these and other useful ends the invention consists in matters hereinafter set forth and claimed and shown in the accompanying drawings, in which—

Fig. 1 is a side elevation of a portable conveyor embodying the principles of the invention, showing the hopper body of the coal car in cross section, and showing the track in cross section, with the said conveyor disposed in position to receive the coal from the said hopper body of the car.

Fig. 2 is a plan of the conveyor shown in Fig. 1.

Fig. 3 is a vertical cross section on line 3—3 in Fig. 1.

Fig. 4 is a vertical cross section on line 4—4 in Fig. 1.

As thus illustrated, the invention comprises side bars or sills 1, preferably of channel iron, suitably connected together by end bars 2 to form a rectangular frame. This frame is mounted on wheels 3 which are carried by axles 4 mounted in blocks 5 which slide up and down in the guides 6, hand screws 7 being provided for the adjustment of the axles up and down in said guides, so that the body frame can be raised and lowered at will. Said wheels 3 travel on rails 8

supported in any suitable manner, it being observed that these rails 8 are disposed at right angles to the rails 9 of the main track upon which the wheels 10 of the hopper car body travel, said car being of any well known form or construction. A horizontally disposed plate 11 is arranged between the sides 1 of the rectangular frame, said plate having up-turned side flanges 12, so that it is adapted to receive the coal or other materials from the said car. This plate reciprocates endwise, and for this purpose is supported by wheels 13 that travel in the channel irons 1 of the body frame. Skirt 70 boards 14 are hinged to the body frame at 15, and a similar end board 16 is also hinged to the body frame, thereby forming a sort of hopper to receive the discharge of the coal or other materials from the car. A shaft 17 is suitably mounted transversely on the body frame, near the end thereof, and is provided with crank devices 18 which are connected by pitmen 19 with the plate 11, whereby the latter is reciprocated back and forth, endwise, such reciprocation causing the coal or other materials to gradually work along toward the edge 20 of the reciprocating plate, and to then fall upon the deflector 21 and from the latter upon the conveyor belt 22 that leads to the place where it is desired to deliver the coal or other materials. A motor 23 is suitably connected with the shaft 17 to drive the latter at the desired speed. Swinging props 24 are provided to hold the boards 14 and 16 in raised position, it being understood that these boards and said props are adapted to fold over flatwise upon the conveyor when not in use.

After the cars have been shifted to bring one of the hopper-like bodies opposite the rails 8, the unloading apparatus is then shifted on its wheels 3 until it projects under the car body, as shown in Fig. 1, and the boards 14 and 16 are adjusted in raised position, whereby the discharge from the bottom of the car will be received on the plate 11, and conveyed by the reciprocating motion of the latter to the point of discharge, as previously stated. The hand screws 7 are adjusted, preferably, until the side members 1 of the rectangular body frame rest upon the rails 9 of the main track, so that these rails will sustain the weight of the materials discharged from the car. Inasmuch as the boards 14 and 16 prevent the materials from spreading in three directions only, it

2

follows that the materials can spread in the fourth direction, toward the edge 20 of the reciprocating conveyer plate, and the back and forth motion of the said plate causes the materials to gradually shift along until they fall upon the deflector 21 and from the latter upon the belt conveyer 22 by which the coal or other materials are carried upwardly to a point where they are then discharged into a wagon or into another car, or into any desired receptacle, or upon the ground. After the materials are all discharged and carried away from the car, the latter is then shifted and another car is brought into position, it being understood that the hand screws 7 are adjusted to raise the conveyer body frame from the track rails, so that the entire apparatus can be pulled away from the rails 9 to permit the shifting of the car on the main track. As soon as another loaded car is in position, the unloading apparatus is then pushed back over the rails of the main track, and the hand screws 7 are adjusted to again lower the rectangular body frame upon the rails of the track and the unloading operation is then repeated. In this way, an apparatus is provided for conveying the coal directly from the car to a wagon or other car, or otherwise, as stated, without the necessity of constructing deep loading pits and storage bins for the coal, and in a way that permits rapid and easy unloading of the cars, one after the other, for the desired purpose, such as in handling coal or any other materials which can be handled and conveyed by the apparatus shown and described. The belt conveyer 22 may be of any suitable character, of course, but is preferably adapted to be moved so that it may be taken out of the way when it is desired to roll the conveyer or feeder having the wheels 3 along the rails 8, when the apparatus is shifted either toward or away from the car. The lower end of this belt conveyer may be disposed in a shallow recess or pit formed in the ground, as shown in Fig. 1; but it will be understood that the means for carrying the materials away from the apparatus may be of any suitable, known, or approved form.

What I claim as my invention is:—

1. A portable conveying apparatus comprising a body frame, a reciprocating feeder supported by said body frame, means for supporting said body frame to extend transversely of a car track to enable said feeder to receive the discharge from a car, and mechanism adjacent the outer end of said frame to reciprocate the feeder in a horizontal plane to produce a shifting movement of the materials thereon, with a discharge space between said feeder and said mechanism.

2. A structure as specified in claim 1, said

means comprising wheels for said body frame, together with rails on which said wheels travel, one end portion of said body frame and reciprocating feeder being adapted to overhang the rails of said car track, so as to extend under the car which discharges from the bottom thereof, means to hold the discharge on the feeder, means to raise and lower said body frame, so that the body frame may be lowered to rest upon the rails of the car track below the car, and means for receiving and carrying away the discharge from said reciprocating feeder.

3. A structure as specified in claim 1, one end portion of said body frame and reciprocating feeder being adapted to overhang the rails of said car track, so as to extend below a car which discharges from the bottom thereof, in combination with means for lowering the body frame onto said rails.

4. A structure as specified in claim 1, said mechanism comprising a motor mounted on said body frame and gear connected to the discharge end of said reciprocating feeder, so that the feeder is operated to take the discharge away from the car.

5. The combination of a car track, a track extending laterally from one side of said car track, a body frame mounted on wheels to travel on said laterally extending track, one end portion of said body frame being adapted to extend over the car track, conveying means on said body frame to receive the discharge from the bottom of a car standing on the car track, and means for operating said conveying means.

6. A structure as specified in claim 5, in combination with screw mechanism for lowering said body frame onto the rails of the car track, so that the latter will sustain the weight of the discharge from the car.

7. A structure as specified in claim 5, in combination with means whereby said body frame may rest on the rails of the car track below the car.

8. A conveyer for feeding materials horizontally, comprising a reciprocating feeder having a projecting end portion which can be inserted horizontally across a track under a car, mechanism to reciprocate said feeder over the track, thereby to produce an intermittent progressive shifting of the materials thereon, and wheels whereby the entire conveying and feeding apparatus is portable and adapted to be shifted from one place to another.

9. A portable conveying apparatus comprising a body frame, a reciprocating feeder supported by said body frame, mechanism to reciprocate the feeder to produce a shifting movement of the materials thereon, and means whereby said body frame is readily movable from one place to another, said means comprising wheels for said body frame, together with rails on which said

wheels travel, one end portion of said body frame and reciprocating feeder being adapted to overhang the rails of a car track, so as to extend under the car which discharges from the bottom thereof, means to hold the discharge on the feeder, means to raise and lower said body frame, so that the body frame may be lowered to rest upon the rails of the car track below the car, and means for receiving and carrying away the discharge from said reciprocating feeder.

10. A portable conveying apparatus comprising a body frame, a reciprocating feeder

supported by said body frame, mechanism to reciprocate the feeder to produce a shifting movement of the materials thereon, and means whereby said body frame is readily movable from one place to another, one end portion of said body frame and reciprocating feeder being adapted to overhang the rails of a car track, so as to extend below a car which discharges from the bottom thereof, in combination with means for lowering the body frame onto said rails.

FRED E. SCHWALB.
